UNITED STATES PATENT OFFICE.

AMOS LIVINGSTON, OF OWEGO, NEW YORK.

COMBINED METALLIC CROSS-TIE, RAIL-BRACE, AND FASTENER.

1,254,419.

Specification of Letters Patent. Patented Jan. 22, 1918.

Application filed April 20, 1917. Serial No. 163,416.

To all whom it may concern:

Be it known that I, AMOS LIVINGSTON, a citizen of the United States, residing at Owego, in the county of Tioga and State 5 of New York, have invented a new and useful Combined Metallic Cross-Tie, Rail-Brace, and Fastener, of which the following is a specification.

This invention relates to a combined metallic cross tie, rail brace and fastener for railroad tracks.

An object of the invention is to provide a metallic construction of tie and rail brace, which can be easily adjusted to the curve of 15 the road bed, which will permit the use of shorter rails, with less space between the ends of the rails for expansion and contraction, thus saving the wear on the ends of the rails.

Another object of the invention is to provide a resilient rail fastener to be driven or forced over the base flange of the rail, whereby creeping of the rail is prevented, fish plates are rendered unnecessary, and the 20 wearing life of the rails greatly increased.

In the accompanying drawings I have 25 illustrated one embodiment of my invention in which:

Figure 1 is a perspective view of a section of track, showing the application of the invention thereto.

Fig. 2 is a longitudinal sectional view of the track illustrating a modified form of rail fastener thereon.

Fig. 3 is a transverse sectional view on the 35 line 3—3 of Fig. 2.

Fig. 4 is a detail view of another modified form of rail fastener.

In the embodiment of the invention here illustrated, the metallic construction which 40 is preferably of steel, comprises a pair of transversely extending ties or bracing members 1 and 2. These are shown as flat bars set on edge. To each end of each tie, upon opposite sides thereof, are secured channel bars 3 having vertical webs 4, which engage the ties and are fastened thereto by means of rivets or other suitable fastening devices 5. These channel plates 3 have horizontally extending oppositely directed lower flanges 6 45 arranged in alinement with each other and in substantially the same plane, and upper horizontally extending oppositely directed flanges 7 likewise arranged in alinement with each other and in substantially the

same plane. The channel plates 3 are located at the joints of the rails.

Located substantially midway between each pair of transversely extending members or ties 1 and 2 at each side and between the ends of the rails are transversely extending flat plates 8 to the opposite sides of which are attached channel plates 9 which I shall term the intermediate channel plates. These channel plates comprise vertically extending web portions 10 fastened to each side of the plate 8 by means of rivets or other suitable fastening devices 11, lower horizontally extending oppositely directed flanges 12 arranged in substantially the same plane and in alinement with each other, and upper horizontally extending oppositely directed flanges 13 arranged in alinement with each other and in substantially the same plane and providing a support for the rail. The lower flanges 12 of each plate 9 are long enough to overlap the lower flanges 6 of the channel plates 3 at one side of the track and located between the ties 1 and 2. Each pair of overlapping flanges 6 and 12 are adjustably fastened together by means of bolts 14 55 fixed to the flanges 6 and riding in slots 14^a of the flanges 12, the bolts being provided with nuts 14^b whereby the flanges are clamped together. By providing a sliding engagement between the overlapping flanges 6 and 12 at each side, the structure may be 60 adjusted to the curve of the track. The upper flanges 7 and 13 of the plates 3 and 9 being spaced apart or separated do not interfere with this adjustment.

It will be seen that I have provided a very rigid construction in which spreading or any other movement of the rails is prevented. The flanges 6 and 12 provide a substantially continuous base support beneath the rails 95 and extending lengthwise along the rails, while the rails are secured to this structure at spaced distances apart by the upper horizontal flanges 7 and 13 described.

In order to secure rails 15 to the upper 100 horizontal flanges, I have provided angular fasteners 16 of resilient sheet steel or similar material. Each fastener is formed of heavy sheet metal bent at an acute angle and comprises the jaws 17 and 18, between 105 which the base flange 19 of the rail is wedged by a driving fit. The construction of the seat of the fastener is such that the base

flange will be tightly clamped and pinched, between the jaws 17 and 18 which are wider than said flange. Bolts 20 extend through the jaws 17 and 18 of each fastener, and the 5 upper horizontal flanges 7 and 13 and securely hold the jaws of the fasteners to the base flange of the rail, and secure the rail to the flanges 7 and 13 by means of nuts 21. These bolts and nuts also assist in tightly 10 clamping the jaws about the rail flange. The flanges 7 and 13 of the channel plates 3 and 9 are of a width transversely sufficient to support the opposed fasteners, which rest upon said flanges.

15 As the fasteners 16 overlap the joints 22, fish plates will be unnecessary.

As shown in Fig. 2, the fasteners 17 extend substantially the entire length of the rails, and cover the base flanges thereof, 20 whereby the rail is materially strengthened and breakage thereof is prevented. As shown in Fig. 1, however, the fasteners are narrow and several are spaced apart along the side of each rail.

25 The fastener 23 illustrated in Fig. 4, may, however, be used, if so desired. This fastener comprises the upper jaw 24 and the lower jaw 25, which is of a length more than twice that of the upper jaw, and is 30 adapted to extend entirely across the bottom of the base flange of the rail, instead of only half way across. Openings 26 and 27 are provided in the fastener 25, through which bolts are adapted to be inserted for 35 fastening the same to the metallic structure or to a wooden tie (when such is used) and for clamping the jaws against the base flange of the rail.

In the construction shown in Figs. 1 to 3, 40 the fasteners have jaws of substantially the same width, the upper jaw of each fastener fitting the upper side of the base flange of the rail and extending beyond the edge thereof to receive the bolts 20, while the lower 45 jaw forms a seat or chair for the rail, covering substantially one-half of the bottom of the base flange, and also extends beyond the edge of the base flange to receive the bolts 20. When fasteners of the above type are 50 used, they are arranged in pairs directly opposite each other on opposite sides of the rail. It will be readily understood that the fasteners 16 may be applied to rails supported on wooden ties.

55 While I have shown and described the preferred embodiment of my invention, it is to be understood that I do not desire to be limited to the details of construction herein shown and described, for obvious modifications will be apparent to anyone skilled in the art.

What is claimed is:—

1. In a metallic cross tie and brace, spaced transversely extending ties, spaced 65 channel plates having their webs fastened

to said ties at the ends thereof, and having upper and lower flanges projecting from opposite sides of the ties, and means for detachably connecting together the lower flanges of the plates adjacent to each other. 70

2. In a metallic cross tie and brace, the combination with spaced transversely extending ties, of spaced channel plates having their webs arranged vertically and fastened to the ties at the ends of the latter, 75 the ends of the ties and the plates extending beneath the rails, said plates having upper and lower horizontally disposed flanges, the width of said upper flanges being materially greater than the width of the base 80 flanges of the rails, whereby when the rails are placed upon the upper flanges, a space is left on each side of the base flanges of the rails, rail fastening means supported in said spaces and connected to the upper 85 flanges of the channel plates, and means for connecting the lower flanges of the plates in one continuous series.

3. In a metallic cross tie and brace, spaced transversely extending ties extended beneath the rails at their ends, said ties being formed of flat bars set on edge, channel plates having their webs fastened to the ends of said ties and also arranged beneath the rails, and comprising upper and 95 lower horizontal flanges, the lower flanges being longer than the upper flanges, means for securing the base flanges of the rails to the upper flanges, and means for connecting the lower flanges of adjacent 100 plates.

4. In a metallic cross tie and brace having a substantially continuous base extending the full length of the rail, and comprising overlapping portions having a bolt and 105 slot connection with each other, whereby the base can be adjusted around curves, vertically extending portions rising from said base and terminating at their upper ends in horizontally arranged spaced apart 110 supports, and means for securing the rail to said supports.

5. In a metallic cross tie and brace, spaced transverse ties extended beneath the rails at their ends, channel plates fastened to the 115 ends of said ties and also arranged beneath the rails and comprising upper and lower horizontally extending flanges with an intermediate web fastened to the ties, intermediate channel plates arranged between the first mentioned channel plates and comprising vertical webs fastened together, and upper horizontally extending flanges and lower horizontally extending flanges projecting in opposite direction, said horizontal flanges overlapping the horizontal flanges of the first-mentioned channel plates, and a bolt and slot connection between said horizontal flanges for adjustably 120 fastening them together. 125

6. The combination with a tie and rail, of a fastener comprising an angular plate providing spaced jaws adapted to be tightly clamped upon the base flange of the rail, and securing devices extending through the jaws and fastened to the tie. 35
7. The combination with a tie and rail, of a fastener comprising an angular plate having spaced jaws tightly clamped upon the base flange of the rail, and securing bolts 10 extending through the jaws and fastened to the tie. 40
8. A rail fastener composed of metal bent to form spaced resilient jaws adapted 15 to be wedged upon the base flange of a rail, and bolts extending through the jaws of said fastener to draw the jaws more firmly together. 45
9. The combination with a tie and a rail having a base flange, of a flexible resilient angular fastener having jaws clamped to each side of said flange and having a greater width than said flange so as to project beyond the edge of the same, bolts for clamping 20 the jaws against the base flange, said bolts extending through the projecting portion of said jaws and secured to the tie. 50
10. The combination with a rail, of a cross tie and brace having channel plates 25 arranged transversely beneath the rail, said 55

plates having their upper horizontal flanges constituting supports upon which said rail rests, and angular fasteners engaging the base flange of the rail and resting upon and secured to said horizontal flanges at each side of the rail base. 35

11. In a metallic cross tie and brace, spaced ties, channel plates having their webs fastened to said ties at the ends thereof, and having upper and lower flanges projecting from opposite sides of the ties, means for detachably connecting the lower flanges of adjacent plates together, and means on the upper flanges for fastening rails thereto. 40

12. In a metallic cross tie and brace, spaced transversely disposed ties, channel plates having their webs secured to said ties at the ends thereof, and having upper and lower flanges projecting from both sides of the ties, the lower flanges being overlapped, 50 and means for detachably and adjustably connecting the lower flanges adjacent to each other in their overlapped relation. 45

In testimony that I claim the foregoing as my own, I have hereto affixed my signature in the presence of two witnesses. 55

AMOS LIVINGSTON.
